UNITED STATES PATENT OFFICE.

MICHAEL G. DELANEY, OF DETROIT, MICHIGAN, ASSIGNOR TO THE NORTHERN SALES CO., OF TOLEDO, OHIO, A CORPORATION OF OHIO.

MOVING-PICTURE MACHINE.

1,144,696.

Specification of Letters Patent. Patented June 29, 1915.

Application filed February 16, 1914. Serial No. 818,912.

To all whom it may concern:

Be it known that I, MICHAEL G. DELANEY, a citizen of the United States of America, residing at Detroit, in the county of Wayne 5 and State of Michigan, have invented certain new and useful Improvements in Moving-Picture Machines, of which the following is a specification, reference being had therein to the accompanying drawings.

10 This invention relates to a moving picture machine and to an arrangement thereof whereby films are readily drawn past the projecting lantern from either side or center delivery carriers or reels in such manner as 15 to automatically maintain a proper tension upon the films.

The invention consists in the matters hereinafter set forth and more particularly pointed out in the appended claims.

20 In the drawings, Figure 1 is a view in side elevation of the upper portion of a film projecting mechanism and film magazine or casing thereon disposed to handle a film from a center delivery reel, the mechanism embodying features of the invention; Fig. 2 is 25 a view in rear elevation of the mechanism; Fig. 3 is a view in vertical section through the film casing; Fig. 4 is a view of the front of the casing with the cover removed, showing an inserted central delivery reel; and 30 Fig. 5 is a bottom plan view of the casing with cover removed and partially broken away, showing the details of a tensioning device.

35 Referring to the drawings a projecting machine 1 has a suitably operated train 2 including a feeding wheel 3 for drawing a picture film from a magazine. This portion of the device may be of any standard or suitable type as the film projecting mechanism does not *per se* form a part of the invention. A member 4 is mounted by supports 5 on the frame of the device 1 as a support for a longitudinally adjustable bracket 7. A pair of 45 cap screws 6 or clamping bolts on the member 4 engage horizontal slots in a bracket 7 whereby the latter may be shifted longitudinally on the member 4 for adjustment purposes. The bracket is arranged to receive a 50 depending stem 8 of a film magazine 9 and thereby support the latter in operative relation to the projecting machine when the casing either is turned in the position indicated for drawing a film from a center delivery reel or for delivering from a sidewise

reel. In the former instance a stud or dowel 10 engages the bracket and maintains the parts in proper relation to the projecting mechanism. In the latter instance the casing is turned at right angles to the position 60 shown with the stud 8 inserted in the socket originally occupied by the dowel 10, a stop 11 engaging a recess 12 in the head of the stud and locking the parts in this position.

A centrally disposed bearing 13 is formed 65 on the back of the casing and a shaft 14 is journaled therein. The portion of the shaft within the casing is adapted to non-rotatably engage with and support a center delivery film reel 15. The latter is maintained in 70 position when in place by a guard arm 16 that is hinged at one end to the side of the casing and is locked by a suitable latch 17 over the shaft end to prevent endwise dislodgment of the reel. A guide roller 18 is 75 journaled between a pair of ears 19 on the reel adapted to engage between the pair of lugs on the arm to properly turn a film drawn from the center opening of the reel so that the film may pass readily through a 80 notch or recess indicated at 20 in the margin of the lower side of the casing.

A yoke 21 is mounted in suitable guides 22 on the under side of the lower wall of the casing 1 with spring members 23 so disposed as to yieldingly project the yoke, whose middle portion spans the recess 20 toward the front of the casing. A guide roller 24 is journaled on the yoke at the opening 20 in vertical alignment with the guide roller 18 90 engaged between the lugs of the guard arm 16. Preferably the yoke is in the form of a bar bent between its ends to provide a pair of parallel arms. At any rate, the yoke has an extension whose end portion 37 lies between spring arms 38 whereby its longitudinal shifting electrically closes or opens the gap between the spring arms 38. The springs 23 are so disposed that they oppose 95 the tendency of a film, such as indicated at 25, to force the roller 24 inwardly.

As a matter of good mechanical construction a shield 39 houses the arms 38 and the latter are connected with binding posts 26. A driving member 27 of a friction clutch is 105 non-rotatably secured to the shaft 14 and is provided with a pair of contact rings 28 with which suitable electrical contact members 29 are in sliding engagement. The clutch member 27 carries an electro-magnet 110

coil 30 whose terminals are connected severally to the rings 28 and to suitable binding posts 31 through the members 29. The binding posts 31 are arranged in series with 5 the terminals 26 and spring arms 38 and are in parallel with the field coils of a motor 32 that is mounted on the casing 9. A suitable driving connection such as worm and gear indicated at 33 couples the motor 32 with 10 a driving member 34 of the main shaft clutch. Said driving member is journaled on the shaft 14 and has slight longitudinal movement thereon so that when the magnet coils 30 are energized by the closing of the 15 gap by the inward movement of the end portion 37 of the yoke 21 the follower member is frictionally engaged by the driving member 34, thereby turning the shaft 14 positively. The circuit connections are indicated diagrammatically in Figs. 1 and 2.

A side opening indicated at 35 is formed in the casing 9 with guide rolls 36 suitably mounted adjacent thereto, the slot and companion rolls being so disposed as to take off 25 a film properly from a side delivery roll when the latter is inserted in the casing and the casing is turned in the bracket 7 at right angles to the position indicated in Figs. 1 and 2, the parts being so proportioned that 30 the film is readily drawn into the projecting machine.

As a result of this construction a film machine is obtained that can be adjusted for taking off a film from a side delivery or 35 shipping reel without rewinding. Thereafter a center delivery reel may be used. The tensioning means prevent any undue strain on the film as the effect of abnormal strain on the latter is to close the circuit and 40 thereby positively drive the reel at such speed that the film would be delivered in such a manner as to relieve the strain. The device is simple and effective and saves the wear and tear on the film due to the re-winding 45 and also due to strains which are put upon the films by use of ordinary machines.

Obviously, changes in the details of construction may be made without departing from the spirit of my invention and I do 50 not care to limit myself to any particular form or arrangement of parts.

What I claim is:—

1. A reel container for moving picture machines comprising a casing, means therein 55 for operatively supporting a reel, a pair of guide rolls at one opening in the casing for receiving a film from a side delivery reel, a tension roll at a delivery opening in the casing for a film from a center delivery reel, and means for supporting the casing on a moving picture machine for delivery 60 through an opening.

2. A reel container for moving picture machines comprising a casing, means therein for operatively supporting a reel, a pair of 65 guide rolls at one opening in the casing for receiving a film from a side delivery reel, a tension roll at a delivery opening in the casing for a film from a center delivery reel, an extension on the casing, a depending stem 70 from the extension, a stud on the extension, and means for interlocking with the stem to support the casing in one position and with the stem and stud to support the casing in the other position. 75

3. A reel container for moving picture machines comprising a casing, means therein for operatively supporting a reel, a pair of guide rolls at one opening in the casing for receiving a film from a side delivery reel, a tension roll at a delivery opening in the casing, for a film from a center delivery reel, an extension on the casing, a depending stem from the extension, a stud on the extension, a bracket adapted to be adjustably supported on a moving picture machine and to interlock with and support the casing in position for delivery from one opening and to interlock with the stem and stud for supporting the casing for delivery from the 90 other opening. 80

4. A reel container comprising a casing, a cover therefor, means in the casing for operatively supporting either a side or center delivery film reel, a pair of guide rolls at 95 one opening in the casing for a film from a side delivery reel, a tension roll on the casing at an opening for delivery of a film from a center delivery reel, an extension on the casing, a stem depending from the extension, a supporting bracket having an opening adapted to receive the stem, a member on the bracket for interlocking with the stem to hold the casing in position for delivery past the guide rolls, and a stud on the 100 extension adapted to co-operatively engage the bracket with the stem for supporting the casing to deliver past the tension roll. 105

5. A reel container for moving picture machines, comprising a casing having a delivery opening for a film, means therein for operatively supporting a reel, a tension roll at the delivery opening adapted to impose a tension on a film after it passes the opening, and means for supporting the casing 110 on a moving picture machine for delivery through said opening.

In testimony whereof I affix my signature in presence of two witnesses.

MICHAEL G. DELANEY.
